CLAIM

The ornamental design for a sprayer nozzle or similar article, as shown and described.

DESCRIPTION

FIG. 1 is a side elevational view of a sprayer nozzle showing our new design;

FIG. 2 is a front elevational view thereof;

FIG. 3 is a top plan view thereof;

FIG. 4 is a right side elevational view thereof, the left side being a mirror image of the right side shown;

FIG. 5 is a bottom plan view thereof;

FIG. 6 is a rear elevational view thereof; and

FIG. 7 is a perspective view taken from the front, top and right side thereof.

The broken line representation of a sprayer in FIG. 1 is for purposes of illustration only.

FIG.1

FIG.2

FIG. 4

FIG. 3

FIG. 5

FIG. 6

FIG. 7
